AUTOMATIC PRESSURE-SENSITIVE
ADHESIVE TAPE DISPENSERArthur A. Anderson, Rose Township, Ramsey
County, Minn., assignor to Minnesota Mining
& Manufacturing Company, St. Paul, Minn., a
corporation of Delaware

Application December 4, 1942, Serial No. 467,891

8 Claims. (Cl. 216—29)

This invention relates to pressure-sensitive adhesive tape dispensers, particularly to those which apply as well as dispense tape, such tape having a pressure-sensitive adhesive coating which is normally tacky without the necessity of being activated by solvents or heat, such as the tape sold under the trade-mark "Scotch."

It provides a novel species of dispenser and applier of the class broadly described and claimed in my co-pending application Ser. No. 400,143, filed June 27, 1941. The latter provides, inter alia, means for severing and thrusting out lengths of tape, and means for applying said lengths to objects.

The present invention has among its objectives 15 the following:

To provide a device which will dispense and apply a piece of tape to the top, bottom and the intermediate side or end or edge surface of objects, such as cards, folders, booklets, and the like, which it is desired to seal and/or label around the edge (see Figures 10 and 11).

To provide a simple device for rapidly sealing and/or labeling objects with accurately measured lengths of pressure-sensitive adhesive tape direct from commercial supply rolls thereof, whose action is entirely automatic once the objects are fed to it.

Briefly the invention provides means for withdrawing tape from a supply roll, cutting it into accurately measured pieces of predetermined length, thrust out a piece and releasably holding it at a dispensing station in a position to be contacted on its adhesive side by a side surface of the object being taped, and sealing means for pressing the piece into adhesive engagement with the top and bottom surfaces of the object.

The device may be designed and/or adjusted to apply tape to relatively thin objects such as cards or to relatively thicker objects such as boxes, bags, packages, cartons or the like.

Such machines may be power driven and equipped with control means whereby they operate intermittently in "dispensing cycles" to position one piece at a time adjacent the applying means in step by step fashion, the control means including a tripping or starting means adapted to start the mechanism again for the next cycle when the preceding piece is removed from the dispensing station. Such tripping or starting means may be actuated by the removal of the severed piece of tape from the dispensing station as described and claimed in my copending application Ser. No. 428,200, filed January 26, 1942; or, as in the machine illustrated herein, it may be 55

actuated by movement of the object to which tape is being applied. The tape may be applied to an object by propelling the object into contact with the thrust-out piece of tape and into contact with the pressing or sealing means. Such propulsion of the object may be by manual movement thereof (as illustrated in the said application S. N. 400,143) or by a power driven propelling means (as illustrated herein).

The machine that is described and illustrated in the following description and drawings as illustrative of my invention is a portable electrically driven tape dispenser and card sealer whose action is entirely automatic once the cards are fed to it, particularly suited for use in offices, stores, mailing departments, circularizing bureaus, etc., for labeling and/or sealing the edges of cards, folders, circulars, envelopes, booklets and other relatively thin objects.

In the accompanying drawings and description the end of the machine at which the operator stands when facing the machine to operate it is called the front end, and the terms "right" and "left" are from the point of view of such operator.

Figure 1 is a perspective view of the left and top of the machine.

Figure 2 is a left side elevation with the side wall of the casing broken away and with the applying mechanism above the casing shown in section, the section being taken vertically through the longitudinal center of said mechanism.

Figure 3 is a sectional view of a cutting and gripping unit shaft taken through the unit along the line 3—3 in Figure 5 looking in the direction of the arrows.

Figure 4 is a sectional view of the same shaft taken at a point to show the cam in left side elevation, along the line 4—4 in Figure 5, looking in the direction of the arrows.

Figure 4a is a sectional view of a cam and part of the wheel taken along the axes of the shaft and the brake pin, as shown by the line 4a in Figure 4.

Figure 5 is a plan view with the applying mechanism and top of the casing broken away.

Figure 6 is a front view with the front wall of the casing broken away.

Figure 7 is a right side elevation of the switch mechanism.

Figures 8 and 9 are wiring diagrams.

Figures 10 and 11 are perspective views of a card and a box, respectively, showing the manner in which tape is applied by devices embodying this invention.

Within the casing and toward the rear of the machine, a supply roll R of tape T is mounted

on a drum 16 which is journaled on an unthreaded portion of a horizontal axle-bolt 17 adjacent the knurled bolthead 17a. The bolt is in threaded engagement with a rearwardly extending arm 18a of the upright frame 18 which is fixed to the base 19.

Forwardly of the supply drum is the wheel 20 which withdraws the tape from the roll by tape-gripping means positioned thereon adapted to contact a portion of the tape, there being also means on the wheel and means adjacent thereto adapted to form two coacting severing means positioned so that the tape is pressed therebetween as the wheel rotates, thereby severing the tape with the severed piece still held by the gripping means. In the present embodiment the severing means on the wheel is in the form of cutting edges x and the coacting severing means adjacent the wheel is an anvil member in the form of a cylinder 21.

The wheel 20 is fixed on a shaft 22 which is journaled in the frame 18 preferably perpendicular thereto and parallel with the base 19 and with the axis of the supply drum 16.

A plurality of shafts 23 (there are six in the present embodiment, spaced 60° apart) are journaled in the wheel's peripheral portion parallel with the wheel's axis. To each shaft is fixed a "unit" 24 which carries a severing means and a gripping means, each unit holding a blade 25 having a cutting edge x and a tape-gripping surface a (Figure 3), and each unit being shaped to form a second tape-gripping surface b in line with a . The grippers a and b releasably hold the tape by adhesive contact. The blades 25 are removably held by screws 26 so that the blades may be re-positioned from time to time to permit each one of four edges of a blade to serve in turn as the cutting edge x . The units 24 are roughly quadrant-shaped in cross section.

To the right end of each unit shaft 23 is fixed a quadrant shaped cam 23a (Figures 4 and 4a). An arc shaped slot 23b in the left face of each cam receives one of six stopping and braking pins 20a each of which is slidably held in a bore in the wheel and extends outwardly from the right face of the wheel into the slot of the adjacent cam so as to limit the distance which the unit shaft can turn in either direction on its own axis. A compression spring 20b in each bore presses the pin 20a toward the right against the cam so that the pin serves as a brake to prevent accidental turning of the shaft 23 except when forced to turn in the intended manner by cam pins P' and P'' hereafter described.

The cam pins P' and P'' are fixed to the frame 18 adjacent the wheel. P' is positioned so that as the wheel turns, P' strikes a cam 23a on one of the cam's two straight sides to turn the shaft 23 until unit 24 is in dispensing position. P'' subsequently strikes the cam on the cam's other straight side so as to turn the unit back to normal cutting position after the piece of tape has been removed from the gripping surfaces a and b . By "dispensing position" is meant the position occupied by a unit when it is turned so as to serve as a projecting means, holding a severed piece of tape outwardly from the wheel (like the unit which holds the piece T-1 in Figure 2). By "cutting position" is meant the position occupied by a unit when its edge x is positioned to coact with the roller 21 to sever the tape (like all the units in Figure 2 except the unit holding the piece T-1).

A pressing roller 27, rotatably mounted on a

shaft that is fixed in the frame 18, is positioned adjacent the rear of the wheel, to act as an idler roller over which to lead the tape from the supply roll R to the wheel 20, and also to press the tape more firmly into adhesive engagement with the gripping surfaces a and b on the units 24.

The cutting roller 21 which coacts with the severing edges x on the wheel 20 to sever the tape, is journaled on a shaft 30 which is held in threaded engagement with the angle arm 31 at such an angle that the cutting edges x contact the roller point by point along their length as the wheel 20 turns them successively past it. The arm 31 is pivotally mounted at its elbow on a horizontal shaft 32 which is fixed in the frame. The rear end of the arm is slidably pierced by a vertical adjusting bolt 33 which is held rigidly in a bracket 18b. Lock nuts 34 on the shaft limit the downward movement of the arm 31, preferably to a point which will position the cutting roller 21 at the most rearward point to which it comes during a cutting operation. The arm is normally held down against the lock nuts by a spring means 35 (shown as a rubber cushion) that is sufficiently yieldable to permit the roller 21 to be forced forwardly by the pressure of an edge x during a severing operation to the most forward position which the roller is required to occupy during such operation.

The wheel 20 is driven by worm gear reduction motor M (supported on bracket 18c) through a Geneva movement 38 which transmits the rotation of the motor's driving shaft 39 intermittently to the wheel shaft 22 in a manner well known, a movement having been selected here that will rotate the wheel 60° at a time, there being six units 24 on the wheel 60° apart in the illustrated machine.

The machine is enclosed in a casing having a flat horizontal top surface 40 which forms a table or support for guiding objects being advanced towards the tape applicators. An auxiliary feeding shelf with its top surface 40c flush with the surface 40 may be attached to the front of the machine for convenient stacking or beveling of the cards, boxes, etc., that are to be fed to the machine. Lateral guides 9 on the surfaces 40 and 40c help direct the objects as they pass through.

The top surface of the table is preferably slightly above the highest point reached by a unit 24 when the latter is in dispensing position. An aperture 40a (Figure 1) in the table above the wheel 20 permits pieces of tape and certain parts of the machine to project upwardly therethrough, as hereinafter described.

To the rear of the dispensing station (which is the station or locus where a severed piece of tape is held in dispensing position extending upwardly through the aperture in the table in position to contact the object being taped, like the piece T-1 in Figure 2), an idler roller 42 is journaled on a fixed horizontal shaft. It may be of any suitable material, preferably a resilient material such as rubber. One of its functions is to bend or to direct the lower portion of a piece of tape upwardly towards the bottom surface of an object being taped when the advancing object pushes the tape against it; and since it may also serve as a sealing means to press the tape upwardly against the under side of the object, the top surface of roller 42 is preferably approximately flush with the top surface of the table.

Above the table a fixed horizontal cross rod 51 is held by two side bars 51a which are fixed to either side of the casing by bolts 51b. The rod

51 supports an arm 52, which is preferably resilient and which extends downwardly to hold rotatably an idler roller 53 above the lower idler roller 42, sufficiently above the top of table 40 to permit objects being sealed to pass under it. It may be of any suitable material, preferably a resilient material such as rubber. One of its functions is to bend or to direct the upper portion of a piece of tape downwardly towards the top surface of an object being taped when the advancing object pushes the tape against the roller; and since it may also serve as a sealing means to press the tape downwardly against the top side of the object, the lower surface of roller 53 is preferably approximately flush with or slightly lower than the top of objects being taped (i. e., objects to which tape is being applied). The distance between the upper and lower rollers 53 and 42, respectively, is determined by the height of the objects.

To the rear of the lower idler roller 42 is a switch trip 44a extending upwardly through the aperture 40a above the table top so as to be engaged by the advancing object sufficiently to activate a switch mechanism hereafter described. The trip is fixed to a horizontal trip shaft 44 journaled in frame 18 and extending therethrough. The trip is held in a normal open switch position by the upward pull of the spring 45 on the spring arm 44b which is fixed to the trip shaft 44. The distance which the arm 44b may be moved upwardly by the spring is limited by suitable stops (not shown) which extend outwardly toward each other from the arm 44b and the frame 18, respectively, so as to engage each other when the arm has reached the desired open switch position. On the right side of the frame 18 a switch arm 44c is fixed to the trip shaft 44 in a position to be normally clear of the "on" point 46a of a reset micro switch 46 and to depress the point when the switch trip 44a is engaged by the object being sealed.

By a "reset" switch is meant one having two pins, one of which is pressed to make a circuit and the other to break it, such that when the "on" pin is pressed, the switch remains closed until the "off" pin is pressed, whereupon the switch opens and the "on" pin is raised to initial open position.

With the power line switch S closed, closing the switch 46 completes the circuit (Figure 8) and it remains so until broken by pressure against the "off" pin 46b by the leaf spring switch arm 47 which is mounted so as to be pressed by switch cam 48 or 48'. It is well known that after a driven Geneva wheel stops, the driver idles or rotates alone for a distance before engaging the driven wheel again. The cams 48 and 48' are adjustably mounted on the motor's driving shaft 39 at a point to shut the power off so that the motor coasts to a stop during the idling period of the Geneva driver wheel which is fixed on the shaft 39 in the Geneva movement 38. The wheel 20, to whose shaft 22 is fixed the driven Geneva wheel, is thus brought to a stop precisely at the end of each dispensing cycle (i. e., after a length of tape has been withdrawn, severed and thrust out in dispensing position) and it remains stopped until the switch trip 44a is again moved to close the switch 46 to initiate the next dispensing cycle.

The illustrated machine as thus far described, provides a device that will automatically withdraw, sever, and apply accurately measured sin-

gle lengths of tape to the top, bottom and intermediate side surface or edge of objects that may be propelled by hand across the table 40 between the rollers 42 and 53. Features are hereafter described which provide power driving means for so propelling the objects and ejecting them.

Below the fixed rod 51 is a movable horizontal frame which comprises a fixed rod 56, a power shaft 57 and a fixed rod 58 held between two longitudinally extending end bars 59. Shaft 57 is journaled in the bars; rods 56 and 58 are fixed therein. The frame thus formed is pivotally held at 60 by four side bars 61 (two on either side of the machine) which, in turn, are pivotally held at their lower ends at 62 to the sides of the casing, so that the frame may be raised and lowered in respect to the table top 40 without changing its angular relation thereto. It is raised and lowered by a nut or thumb turn 63 on a threaded stud 64 which slidably pierces the fixed rod 51 and which is removably fixed (by threaded engagement) to a collar 65 that is fixed to the rod 56. A spring 66 around the stud 64 impels the frame downwardly.

Twin idler pulleys 56a journaled on rod 56 and twin power pulleys 57a fixed on power shaft 57 support two endless propelling belts 67 which propel objects rearwardly along the top 40 by frictional engagement of the lower flights of the belts with the tops of the objects which are thereby slid across the smooth surface of the table. There may be more than two propelling belts, if the width or frictional resistance of the objects makes a greater propelling force desirable. It is sometimes advantageous to provide relatively narrow elongated slots 40b (Figure 6) immediately below the belts 67, especially when the objects being sealed are cards or other relatively thin objects. These permit lowering the belts until their bottom surfaces are approximately flush with the top surface of the table 40, thereby increasing the friction between the belts and a card with a minimum of frictional increase between the card and the table.

A motor M' fixed to the inside of the casing with its driving pulley 68 projecting outwardly therefrom, rotates the power shaft 57 clockwise (Figure 1) by means of the belt 69 and the pulley 57b which is fixed to the shaft. Power is supplied to the motor M' through switch S'. A large roller 70 may be fixed on the shaft 57 between the pulleys 57a to assist in propelling the objects and/or in pressing tape downwardly against the top of the objects.

An upper guide member 71 is fastened to the collar 65 and extends therefrom rearwardly to a point beyond where the object contacts the tape. At its rear end its central portion is preferably cut away forming a rectangular aperture 71a (Figure 1) to permit the severed pieces of tape to clear it as they are moved up into dispensing position by the wheel 20 from below. The objects pass between the guide 71 and the table top 40 when being propelled through the machine towards the severed piece of tape T-1.

To the rear of roller 42 is shown a second idler roller 43. This may be raised slightly above the table top to relieve the friction between the moving object and the table. It may also serve as a sealing roller to press the tape against the bottom of the object.

Mode of operation

A roll R of pressure-sensitive adhesive tape T is mounted on the drum 16 in a position so that

when the tape is led from the supply roll R to the wheel 20, the adhesive side faces up. The axle-bolt 17 on which the drum 16 is journaled, is moved to the right or left (in relation to the machine) by turning the bolt-head 11a until the roll R is aligned directly behind the units 24 on the wheel 20.

The tape is led from the roll R over the pressing roller 27 and trained around the wheel 20 in adhesive contact with the gripping surfaces a and b. In practice, training the tape around the wheel is best done by hand as far as the unit which is adjacent the cutting roller 21 and then by the power mechanism for the rest of the way, that is, until the first severed length of tape T-1 is held out by a unit 24 at the dispensing station (Figure 2). Such movement or training of the tape by the power mechanism (whose operation is hereinafter described) is secured by turning on the switch S and then depressing the switch trip 44a by hand repeatedly until the wheel 20 has turned through the desired distance.

The movable frame which carries the propelling belts 67 above the machine, is moved up or down by turning the thumb-turn 63 until the card, box or other object being sealed will pass between the lower flight of the belts and the table surface 40 with a frictional engagement between the belts and the object sufficient to propel the object in the direction of movement of the belts. Switch S' is then turned on whereupon motor M' continuously rotates the propelling belts in the direction of the arrow in Figure 2.

The card, box or other object to which tape is to be applied around an edge thereof in the manner shown in Figures 10 and 11, is placed on the shelf surface 40c and moved manually in the direction of the arrow (Figures 1 and 2) until it is nipped between the belts and the surface 40, whereupon the belts propel it towards the rear of the machine through the channel formed by the guide member 71 above and the surface 40 below. When its leading side or edge strikes the adhesive side of the upwardly held piece of tape T-1, the tape adheres to the object so as to be removed from the gripping surfaces a and b which are on the unit 24. This operation is facilitated, especially in the case of extremely flexible objects such as thin cards and paper folders, by the guide 71 which bears close against the top of the card and extends rearwardly on either side of the piece of tape T-1, thereby holding firm that portion of the card adjacent its edge at the point where that edge is to strike the tape, at the moment that such striking occurs.

The object thence proceeds onward with the vertically extending length of tape adhering to the object's leading edge or side, the upper and lower ends of the tape projecting above and below the top and bottom, respectively, of the object. Upon reaching the rollers 53 and 42, the upper and lower free ends of the tape are directed thereby towards the object's top and bottom, respectively. The rolls 53 and 42 may bear closely enough so that one or both serve also as sealing means to press the tape against the top and/or bottom of the object; or the guide roller 43 may seal; or the roller 10 that is between the pulleys 51a may seal. The sealing means for pressing the tape against the object need not necessarily be in the form of rollers. Bending and sealing the ends of the tape against the top and bottom surfaces of the object serves also to effect adequate

sealing or adherence of the tape to the leading edge, side or end thereof as well.

The object then strikes the upwardly extending switch trip 44a and passes over it thereby depressing it sufficiently to close the switch 46 by forcing the switch arm 44c against the "on" point 46a. After the object passes beyond the switch trip 44a the spring 45, acting on the arm 44b, returns the trip 44a and the switch arm 44c to their normal positions.

The said pressing of the "on" point 46a of the switch 46 starts the motor M whose driving shaft 39, acting through the Geneva movement 38, rotates the wheel 20 on the shaft 22 precisely 60°. The switch cam 48 (or 48') fixed on shaft 39 is set so that it presses the switch arm 47 against the "off" point 46b of the switch 46 thereby shutting off the power from the motor M at such a time (usually at or about the end of the 60° of turn of the wheel 20) that the motor will coast to a stop within the idling period of the driver Geneva wheel before the said driver again engages the driven Geneva wheel for the next 60° of turn.

The tape, as previously explained, is trained around the wheel 20 in contact with the tape-gripping surfaces a and b on the units 24, and it also passes over the severing edges x which are also on the units. As the wheel turns counterclockwise (Figure 2) it withdraws the tape from the roll R, and the edges x successively press against the coating severing element or roller 21, each edge contacting the roller point by point along the edge's length until the entire length of the cutting edge has been pressed against the roller, whereby the tape that lies between the edge and the roller is severed. Upon rotation of the wheel 20 through the "dispensing cycle" (60° of turn) the unit that is shown in Figure 2 as carrying the severed piece of tape T-2, is turned on its shaft 23 by reason of its cam 23a striking the pin P' so that when the wheel stops at the end of the cycle the unit is in dispensing position with the piece T-2 held outwardly and upwardly away from the wheel, like the piece T-1; and during the same cycle the unit that is now shown in dispensing position holding the piece T-1, is turned back down to cutting position by reason of its cam striking the pin P'', the object that is being taped having removed the piece T-1 at the beginning of the cycle as described above.

Thus it is seen that, without touching the tape or any part of the machine, an operator may apply a single length of tape about the edges of a succession of objects simply by feeding the objects to the propelling belts 67. If desired, the motor M', the belts 67 and connecting parts may be dispensed with and the objects propelled between the rollers 42 and 53 by hand. Tape may be applied about the edge, top and bottom of relatively thin objects such as cards; if the card be double like a postal with return postal attached, the tape may seal the card by holding its two free edges together like the piece 75 in Figure 10. Tape may be applied about the edge, top and bottom of relatively thick objects such as boxes, like the piece 76 in Figure 11.

The word "card" is used herein as a generic term to designate any relatively thin object which may be run through the machine to have a length of tape adhered about its edge. Similarly the word "box" denotes relatively thick objects. The word "tape" is used generically to

refer to sheets that are relatively long in proportion to width.

Dispensing units embodying the principles of this invention may be built into other machines such as printing presses, packaging machines, addressing machines, etc.

It will be apparent that very accurate measurement of lengths of tape can be secured. This is of especial advantage when dispensing tape that is printed to form a series of labels, stickers, trade-mark emblems, etc.

It will also be apparent that the severing means here employed provides a smooth straight cut and the smoothness of the severing members prevents their becoming clogged with adhesive.

I claim:

1. A device for dispensing pressure-sensitive adhesive tape and applying it about the edge of an object comprising means for withdrawing tape from a supply roll, means for cutting it into accurately measured pieces of predetermined length, means for thrusting out a piece and releasably holding it by adhesive contact therewith at a dispensing station in a position to be contacted on its adhesive side by a side surface of the object being taped, and sealing means for pressing the piece into adhesive engagement with the top and bottom surfaces of the object.

2. A device for dispensing pressure-sensitive adhesive tape and applying it about the edge of an object comprising means for withdrawing tape from a supply roll, means for cutting it into accurately measured pieces of predetermined length, means for thrusting out a piece and releasably holding it by adhesive contact therewith at a dispensing station in a position to be contacted on its adhesive side by a side surface of the object with free ends of tape projecting above and below the top and bottom respectively, sealing means positioned to press the ends of the tape against the top and bottom when the object is propelled adjacent thereto, a support for guiding the object, and power driving means and associated control means adapted to automatically advance the next piece of tape to dispensing position after the preceding piece has been applied.

3. The device of claim 2 with power driving means for propelling the object through the machine so that a succession of objects will be taped and ejected from the machine automatically upon being fed to the propelling means.

4. The device of claim 2 with power driving means for propelling the object through the machine comprising a plurality of driven belts positioned to propel the object by contact therewith along the guiding support into contact with the piece of tape at the dispensing station and thence past the sealing means and the control means whereby a succession of objects will be taped and ejected from the machine automatically upon being fed to the propelling means.

5. In a pressure-sensitive adhesive tape dispenser and applier adapted to tape objects about an edge by application of a piece of tape to the top, bottom and intermediate side surface, a table for guiding objects when propelled through the machine having an aperture over which the

objects are passed and through which pieces of tape are fed for application to the objects, an upper sealing roller above the table, a lower sealing roller extending upwardly through the aperture so that its top surface is approximately flush with the top surface of the table, means for projecting successive pieces of tape through the aperture in front of the rollers with the non-adhesive back toward the rollers, the projecting means releasably holding the lower portion only of a piece of tape by adhesive contact therewith below the table top with a free portion projecting upwardly through the aperture above the table top so that when an object is moved across the table and over the aperture the upper free portion will adhere to the side surface of the object and be removed from the projecting means with the upper and lower ends of the piece of tape projecting above and below the top and bottom, respectively, of the object in such alignment that the ends are pressed against the top and bottom by the upper and lower rollers as the object is propelled between them, and means for automatically advancing a succeeding piece of tape into dispensing position following each taping operation.

6. The device of claim 5 with power driving means for propelling the objects through the machine so that a succession of objects will be taped and ejected from the machine automatically upon being fed to the propelling means.

7. An automatic card sealer comprising means for withdrawing pressure-sensitive adhesive tape from a supply roll, means for cutting it into accurately measured pieces of predetermined length, means for successively thrusting out and releasably holding pieces of the tape by adhesive contact therewith at a dispensing station in a position such that each successive piece may be contacted on its adhesive side by the leading edge of a card with free portions of tape projecting above and below the card, sealing means positioned to press the ends of the tape against the top and bottom of the card when the card is propelled adjacent thereto, a supporting surface for guiding the card having an aperture over which the card is passed and through which the piece of tape extends when held at the dispensing station, and power driving means and associated control means adapted to automatically advance the next piece of tape to dispensing position after the preceding piece has been applied.

8. The device of claim 7 with power driving means for propelling the card through the machine comprising a plurality of driven belts positioned to propel the card by contact therewith along the supporting surface into contact with the piece of tape at the dispensing station and thence past the sealing means and the control means, and an upper guide member above the supporting surface forming a passage for the card therebetween and extending on either side of the piece of tape at the dispensing station, whereby a succession of cards will be sealed and ejected from the machine automatically upon being fed to the propelling means.

ARTHUR A. ANDERSON.
